FRANK W. ALSTON, OF SAN FRANCISCO, CALIFORNIA.

TIME-REGULATED RINGING-KEY FOR TELEPHONE-LINES.

SPECIFICATION forming part of Letters Patent No. 690,127, dated December 31, 1901.

Application filed March 5, 1901. Serial No. 49,678. (No model.)

To all whom it may concern:

Be it known that I, FRANK W. ALSTON, a citizen of the United States, and a resident of the city and county of San Francisco, in the State of California, have invented a new and useful Improvement in Time-Regulated Ringing-Keys for Telephone-Lines, of which the following is a specification.

This invention relates to improvements made in electrically-operated ringing or signaling devices, such as are employed in telephone-exchanges for calling up or signaling subscribers. The means generally provided for that purpose consist of a circuit-controlling device, forming part of the operator's outfit at the switchboard and termed the "ringing-key," in circuit with a source of electrical power and with an electrically-operated bell at the subscriber's station or telephone through the usual switchboard spring-jacks and connections, the call or signal being made by the operator depressing the key one, two, or more times, according to the number of rings, strokes, or units of sound that form the distinguishing-signal of the station. In the case of a single telephone stationed on a line a single ringing-key is provided, or where two or more telephones are served by the same line, as in a party-line system, the operator is furnished with a number of individual ringing-keys corresponding in number to the telephones on the circuit. In both cases the number of "bells" or strokes or units of sound that form the individual call are measured and determined by the movements of the key in the hands of the operator, and the evenness and regularity of the rings or strokes, both with regard to the duration of the sound and the pause or interval of rest between them, consequently depend upon the skill of the operator and the special attention bestowed in depressing and releasing the key. Under these conditions and limitations the production of clear and definite signals by a hand-operated key necessarily varies with the skill, as well as the mood, of the operator as influenced by the varying conditions of the work at the switchboard, and it may safely be said that the production of indefinite, unsteady, and confusing signals is always inseparable from the transmission

of signals of this character by a hand-operated key.

The present invention has for its object to overcome the defects and limitations of hand-operated devices by producing a mechanically-operated time-regulated device or mechanism having several novel features and advantages over hand-actuated keys and like devices by which connections are electrically made and broken for operating a bell or other signal. It is under the control of the operator to the extent of being adjustable for producing at will a given number of rings, strokes, or units of sound; but after such adjustment it determines and controls automatically and independently of any manipulation or attention on the part of the operator both the duration of each ring or stroke or sound of the signaling device and the pause or interval of rest between the same, thereby securing regularity and an absolute uniformity in the signals transmitted.

Briefly stated, the invention consists in producing a time-regulated mechanically-operated circuit-controlling device and in certain novel parts and combination of parts, as hereinafter described, and pointed out in the claims at the end of this specification, reference being had to the accompanying drawings, forming part thereof.

The said drawings illustrate the application of these improvements in the production of a ringing-key for a ten-party telephone-line having five stations or telephones on each side of the line.

Figure 1 is a front elevation of a complete mechanism for operating separate calls or signals for ten different telephones served by a single-line circuit from a central station. Fig. 2 is a side elevation taken from the left side of Fig. 1. Fig. 3 is a front elevation similar to Fig. 1, but showing the plunger depressed and the parts in active operating position. Fig. 4 is a detail front elevation of the time mechanism and locking device controlling the plunger. Fig. 5 is a similar view of the same parts representing the plunger depressed. Fig. 6 is a top plan of the plunger and the indicator for setting the circuit-selector of the time-regulating means. Fig. 7 is a horizontal cross-section at 77, Fig. 4. Fig. 8

is a sectional view of the contact-segments in the ringing and time-regulating circuits. Fig. 9 is a detail front elevation of some of the parts herein termed the "time mechanism," 5 including the spring-barrel and the stops and stop-lever that control the movements of the barrel. Fig. 9^a is a top view of the toothed disk and stop-lever of the time mechanism. Fig. 9^b is a detail of the parts connecting the 10 pinion and the spring-barrel together. Fig. 10 is an inverted plan of the stationary contacts forming one part or member of the circuit-selector in the time-regulating means. Fig. 11 is an inverted plan of the movable 15 contacts controlled and set by the plunger and forming the other part or member of the circuit-selector. Fig. 12 is a diagrammatic representation of those parts of the mechanism which enter in or form part of the electric 20 circuits, together with the wiring of the circuits connecting the same with the source of electric power and with the local signals of two distant stations through the usual switch-board-jacks and operator's ringing-plug; and 25 Fig. 13 is a detail view of the cut-out.

Referring to the figures of the drawings, and particularly to the diagram Fig. 12, it will be noticed that the apparatus shown therein has a range or capacity of five different signals 30 on each side of a party-line circuit, calling for five signals, numbered from "1" to "5," inclusive, on the "red" side and five correspondingly numbered on the "black" side. This particular construction, however, is 35 shown and described for the purpose merely of illustrating the scope of the invention and not with any intention of limiting or restricting the same to a ringing device or apparatus for the production or transmission of plural 40 signals on party-line circuits between a central station and distant telephones, for it will be evident from the description hereinafter given that the invention is well adapted also for selecting and applying currents of different 45 character or quality, as a plus or minus or an alternating current, to one or both sides of a metallic circuit simply by wiring the plunger and connecting the contact-segments so as to supply the required currents.

50 The principal parts or members that enter into the construction of the apparatus, whatever may be its capacity or scope as to the number or variety of signals, comprise, first, the plunger-rod *a*, depressed by hand and returned to position by coiled springs 2, acting against a cross-head 3, fast on the plunger; secondly, a locking device holding the plunger after it is depressed against the reactive force of the springs and composed of a locking-latch *b*, engaging a shoulder *d* on the plunger, an electromagnet *f*, normally in open circuit with a local generator *g* and operating as often as it is energized to move the latch and release the plunger, and a set of spaced contact-segments *h* in the circuit between the magnet and the generator; thirdly, a circuit-selecting device composed of a series of sta-

tionary contacts *i*, corresponding in number with the contact-segments *h* and with which they are separately and severally connected, 70 and a movable contact-piece *k*, operative from the plunger and adapted to connect any selected one of the contacts *i* with or throw it in the generator-circuit; fourthly, a plurality of spaced contact-segments *m*, normally connected with one side of the generator-circuit, and, lastly, a traveling circuit-closing device *p*, propelled or caused to travel over the stationary segments *m* by time-regulated driving mechanism, and thereby operating to open 75 and close the ringing-circuit at regular intervals, the length or duration of which is governed by the rate of speed imparted to the traveling circuit-closer.

The plunger *a* performs the several different operations or functions of a circuit-closer to the ringing-plug, a means for selecting and regulating the controlling-circuits of the time mechanism, and a means for winding up the time mechanism. All of these functions or 90 operations are performed or carried out by a simple rotative movement followed by the depression or longitudinal movement of the plunger, thereby enabling all the movements of the mechanism to be effected either directly or indirectly from the one key or plunger. The construction and operation of these parts which control the circuit between the generator and the ringing-plug and which I shall call a "cut-out" will be understood 100 from Figs. 1, 3, 12, and 13 of the drawings, where it will be seen that the plunger *a*, being movable longitudinally in guides provided in the top plate 4 and the bottom plate 5 of the stationary frame, is held up by the 105 coiled springs 2. The contact-blocks *w y*, fixed on the plunger-rod, are composed of two sets of segments set at a fixed distance apart, one 110 below the other, to make contact with the two sets of spring-terminals 6 7 and 8 9, of which the first-mentioned springs are the terminals of wires 10 12, running to the ringing-plug *t*, and the second or lower set 8 9 are the terminals, respectively, of a wire 14, connecting with one side of the local generator *g*, and of 115 a wire 13, connecting together all the segments *m*, herein termed the "ringing-segments." The contact-pieces 55 56 of the upper set *w* on the plunger are separated longitudinally or axially by insulation 59, and those 55 56, 120 composing the lower set, are divided circumferentially of the plunger by the insulation 60, but are also connected electrically by conducting strips or wires 57 58 with the contacts *w* above. By virtue of this arrangement it 125 will be seen that while the springs 8 9 have always the same relative position with reference to the contact-rings of the lower part *y* the connection set up between the springs 6 7 of the upper set and those 8 9 below will be 130 reversed or changed by rotating the plunger, because the members of the contacts *w* being insulated axially will change positions, and where the spring 6, for example, would in one

position be connected by the contact 55 in wire *w* and the corresponding contact-ring 55 in *y* a partial rotation of the plunger will bring the same side of the circuit in connection with the other contact 56 of *w* and through that part with the corresponding ring 56 in *y*, thereby reversing the connections between the generator-circuit and the plunger.

15 is a stationary contact rail or strip connected by the wire 16 with the other side of the generator and setting in close relation to, but properly insulated from, the segments *m*, as those segments are similarly insulated from one another. In this construction the segments *m* are arranged in a circle equidistant from an axis 17, on which the circuit-closing piece *p* is mounted, and the continuous contact rail or strip 15 is formed of a ring or disk, with its flat periphery flush with the exposed 20 or acting faces of the segments. Upon this face as a track the two springs or brushes 18 19 of the circuit-closer *p* are caused to travel at a certain and regular rate of speed by the time mechanism, the details of which are 25 shown in Figs. 4, 5, 7, and 9 of the drawings.

20 is a spiral spring having its inner end connected by a pawl 21 with a spur-pinion 22, loose on the shaft 17, and the outer end attached to the inclosing cylindrical casing 23, 30 which is in turn fixed on the same shaft.

24 is a slide-plate having spur-teeth on the front edge to engage the pinion and a slot 25 in the back edge in which the collar fits loosely. This connection allows the rod to 35 rotate without affecting the plate, while the latter is always connected to the rod and moves up and down with it, and thus longitudinal movement of the rod in one direction acts on the spur-pinion to wind up the spiral 40 spring, but in the other direction the pinion will turn without acting on the spring.

26 is a disk fixed on the shaft 16, with a toothed periphery engaging the lantern-pinion 27 on the arbor of an escapement-wheel 45 28 and also connected with the spring-barrel, so as to be rotated by the power derived from the spring, these parts forming a clock train of well-known character.

29 is a stop-disk attached to the spur-pinion 50 having a shoulder 30, and 32 is an arm loosely pivoted at 33 on the frame, with its free end resting on the rim of the disk.

34 35 are stop-pins on the face of the toothed disk, and 36 is a stop-lever pivotally attached 55 at 37 in the frame, and held by a spring 38 normally in line with the stops and with its free end in line with the collar *d*, so as to be struck and carried down by the rod in its descent. A finger or projection 39 on the outer 60 end of the lever extends under and in the path of the collar, and a toe 40 above the finger, projecting at right angles toward the disk, lies in the path of the inner stop-pin 34 when the plunger is elevated and in the path of the 65 outer stop-pin 35 when the plunger is depressed, thus locking the disk when the plunger is up, and releasing it when the plunger

is down. In the latter position the lever will arrest the disk at the end of every complete revolution by engaging the outer stop-pin. 70 These two positions are represented in Figs. 5 and 9.

The end of the shaft 17 extending to the front through the center of the circle of contact-segments carries the arm *p*, on which are 75 secured the circuit-closing brushes or springs 18 19, one riding on the edge of the continuous rail 15 and the other on the circular face in which the two sets of contact-segments are embedded. By virtue of this construction it 80 will be seen that the spring of the clock-train in the time mechanism is wound up as often as the plunger is depressed and that the same movement of the plunger releasing the toothed disk causes the spring to set the circuit-closing arm *p* in motion, carrying it over the segments and controlling the length or duration 85 of the contact, and also measuring the intervals of rest or interruptions in the current by the rate of speed given to the arm. The construction and operation of that part of the mechanism herein termed the "signal selecting and regulating means" will be understood 90 from Figs. 1, 2, 3, 10, and 11.

The pivoted latch-piece *b*, set in close relation to the poles of the electromagnet, has a shoulder 41 to engage the collar *d*. A spring 42 holds the latch away from the magnet and in position to catch over the collar as the plunger is depressed, and the magnet acting in 100 the contrary direction operates to release the plunger by attracting the latch as often as the magnet is energized. The magnet-windings and the latch-piece are connected by wires 43 44, Fig. 12, with one side of the generator, and also with the other side to establish the circuit, through the medium of the circle of contact-terminals *i*, the contact-segments *h*, connected individually with the contacts *i* by the wires 45, corresponding in number with the segments last named, and the contact-spring 46 and the plunger-rod *a*, through which the latch forming the terminal of one bobbin-winding is electrically connected with a selected one of the set of contacts *i*. 110 115

As represented in Figs. 1, 2, and 3, the circuit-selector *k* is a disk carrying circuit-closing spring 46 and attached to the plunger-rod to turn with it by a pin in the hub working 120 in a groove 47 of proper length to allow the plunger *a* to slide in the disk. The terminals *i* of the conducting-wires 45 are arranged in a circle at regular intervals apart on the bottom of the support 5 over the disk, with the 125 circuit-closing spring 46 in working relation to make contact with any selected one of the terminals on which it may be set.

The segments *h* are interposed between the ringing-segments *m* in alternate order and on the same circle, with insulations of equal length separating one from the other to prevent in the path of the traveling circuit-closer 130 a ringing-segment followed by a time-regu-

lating segment, and in the present construction the latter segments are shorter than the ringing-segments, which are necessarily governed as to their length by the duration of 5 the current required for each operating impulse.

The number and position of the terminals of the selecting device are indicated by the circle of numerals on the top plate 4 of the 10 frame around the plunger, and the position of the circuit-closer with respect to any particular contact-terminal is indicated to the operator by a pointer 50, fast on a sleeve or collar 51, arranged to turn with the plunger, 15 but so arranged or held in the frame as not to be affected by the longitudinal movement of the rod.

In operating the apparatus thus constructed and connected with ringing devices 20 commonly employed on party-line circuits the plunger is rotated until the pointer stands over the numeral on the red or black side of the circuit, which corresponds with the number of the station or the number of bells, 25 strokes, or units composing the desired signal. The plunger then being depressed closes the circuits at the springs 6 7 and 8 9 and is itself locked and held down by the latch b. By that movement of the plunger also sufficient power is stored up in or is added to the 30 spring-barrel, and the lever 36, being simultaneously depressed by the plunger, releases the disk. The circuit-closing arm thereupon begins to move, and carrying the contacts on 35 the outer end over the row of segments makes a complete revolution or travel around the circle. By that operation the current from the generator is thrown in the circuit that includes the signal-producing means as often as 40 the circuit-closer p passes over one of the series of segments, and this continues until the circuit-closer has passed over and in contact with the whole number of segments m, unless 45 before the end of the travel is reached the plunger is released and allowed to rise. This movement takes place at any point in the travel of the circuit-closer where that part comes in contact with one of the shorter or smaller segments h, which has previously been connected 50 with the generator through the selecting device, and at the instant of such contact the circuit between that live segment and the continuous contact-strip being closed the current is passed through the windings of the magnet 55 and the plunger is released by the attraction of the latch to the magnet and the cut-out is withdrawn from contact with the springs 6 7 and 8 9, and the circuits are thereby broken. In this manner one, two, or more of the contact-segments are brought into play while 60 the circuit between the generator and the ringing device is closed by previously selecting and connecting the proper contact-segment h with one side of the generator. In 65 ringing three bells on either side of the circuit, for example, the operator first turns the plunger until the pointer stands over "3"

on the dial, either on the red or black side, thereby setting the selector k on the third terminal i at the bottom of the frame. Then 70 by depressing the plunger the circuit that includes the ringing-plug t and the other circuits, in which are included the ringing-segments m, the generator g, and the continuous strip 15, are closed at the same instant, and 75 the same time the magnet f is brought into the circuit that includes the time-regulating segments h and the generator. Number "3" in the last-named segments, therefore, will be a live segment, for the reason that it will be in 80 direct contact with one side of the generator through the conducting-wire 45, contact i, the selector-spring 46, plunger-rod a, locking-lever b, and wires 43, 44, and 14, thereby causing 85 a circuit to be established with the other side of the generator through the strip 15 and wire 16 as soon as the circuit-closer p reaches the third one of the segments h. In connection with this mechanism also provision is made for controlling the intervals between 90 the signals, so as to allow a reasonable lapse of time for a reply to be received, as in the case of a return-signal, and also to prevent an operator from sending separate signals too rapidly, as in the case of repeating a signal. 95 For this purpose the plunger is locked in the elevated position to which it has been restored after each operation and before the circuit-closing arm has completed its travel and cannot be depressed again until after the 100 circuit-closer has come to rest at the end of its revolution. The device herein provided is a friction-lock composed of an arm 53, loosely attached at one end to the frame and having a straight aperture through it of 105 the same size as the plunger-rod, which is fitted to work smoothly through it as long as the arm sets at right angles to the axis of the rod.

The outer free end of that arm extending 110 across the face of the toothed disk of the time mechanism projects in the path of a stop-pin 54 on the disk, and when unsupported at the outer end the arm necessarily assumes an oblique position with respect to the plunger-rod, thereby throwing sufficient resistance or gripping force on the rod to prevent it from being pressed down. On the other hand, when the arm is brought up to a horizontal position or at right angles to the rod it offers 115 no resistance to the longitudinal movement of that part, and the latter can be readily depressed. The movement necessary to throw off this brake-arm at the proper time is obtained from the toothed disk 26 by fixing the stop-pin 54 at the desired point to strike and elevate the outer end of the brake as the disk reaches the end of its revolution. The interval or period of rest between the transmission 120 of one complete signal and another following it is governed by the adjustment of the clock-train to drive the circuit-closer at greater or less rate of speed as well as by the 125 diameter of the circle in which the latter is 130

required to travel, and according to the standard adopted with respect to the rapidity of the signals and the intervals to be observed between them the size of the circle containing the contact-segments and the spring-driven gearing will vary in dimensions. The pointer 50 will remain over the last number to which it has been set until changed by the rotation of the plunger, thus preventing the possibility of error in repeating the call in case the attention of the operator should be diverted and the number of the call be forgotten.

Having thus fully described my invention, what I claim as new therein, and desire to secure by Letters Patent, is—

1. An electrically-operated signaling device including a time-regulated circuit-closer, a plurality of spaced contact-segments in circuit with a generator and a signal-producing device, a clock-train operating said circuit-closer, a controlling-key and means for variably releasing said key to open the signal-circuit.

2. An electrically-operated signaling device comprising a time-regulated traveling circuit-closer, a plurality of spaced contact-segments in circuit with a generator and a signal-producing device, a clock-train-operated means connected with said traveling circuit-closer, a circuit-closing key, a locking device electrically controlled by the traveling circuit-closer, and adapted to release the key at a predetermined point in the movement of the traveling circuit-closer, and means mechanically restoring the key to position when released and thereby breaking the signaling-circuit when released.

3. In a signaling mechanism for telephone-lines, a time-regulated traveling circuit-closer operative with relation to a plurality of spaced contact-segments in circuit with a generator and with a signal-producing device, and an electrically-controlled locking and releasing means including a plurality of contact-segments in circuit with the generator and the releasing means through the traveling circuit-closer and a selecting device adapted to establish a circuit through a selected one of the releasing-segments and thereby operate the releasing means at that point in the movement of the traveling circuit-closer when it reaches the releasing-segment.

4. A time-regulated ringing-key for telephone-lines including a plunger controlling the ringing-circuit, a plurality of spaced contact-segments, a generator, a traveling circuit-closer, a signal-producing device connectible in circuit with the generator through the ringing-key, and the contact-segments and adjustable time-regulating means controlled by the traveling circuit-closer and adapted to break the ringing-circuit at a predetermined point in the movement of the circuit-closer, and thereby control the number of contacts made by that part.

5. In a mechanically-operated ringing-key, a series of contact-segments in circuit with a

generator and with an electrically-actuated signal-producing device through the ringing-key, a time-regulated traveling circuit-closer adapted by its movement over the contact-segments to open and close the circuit at spaced intervals, a clock-train operating said circuit-closer, means for throwing said clock-train into and out of action, and electrically-operated means controlled from the traveling circuit-closer and adapted to break the ringing-circuit at a point sooner or later in the movement of the circuit-closer.

6. A mechanically-operated time-regulated ringing-key adapted to control the circuit between a signal-producing device and a source of electrical power, as a generator, and comprising a traveling circuit-closer, clock-train-driving mechanism adapted to operate the same, a series of contact-segments in circuit with the generator and the signal-circuit through the traveling circuit-closer, means controlling the driving mechanism and adapted to start and stop the same from the movements of the ringing-key, and means electrically controlled from the movements of the traveling circuit-closer for breaking the connection between the ringing-circuit and the generator at a predetermined period of time in the travel of the circuit-closer over the contact-segments.

7. The combination with a series of spaced contact-segments in open circuit with a source of electrical power and a signal-producing device, of a traveling circuit-closer adapted by its movements to open and close the circuit at intervals through the said segments, a clock-train-driving mechanism operating said circuit-closer, and means electrically operated from the traveling circuit-closer and adapted to open the circuit at a given period of time in the movement of the traveling circuit-closer.

8. The combination with a series of spaced contact-segments in circuit with a source of electrical power and a signal-producing means; of a traveling circuit-closer adapted by its movement to periodically open and close the circuit through the said segments, a clock-train-driving mechanism operating said circuit-closer, means electrically controlled by the said circuit-closer and adapted to open the circuit at a predetermined period in the movement of the circuit-closer and means controlling the driving mechanism.

9. In combination with an electrically-operated signal-producing device; a generator; and a circuit-closing key in open circuit therewith; a spring adapted to throw off the key and open the circuit controlled thereby; a clock-train-operated circuit making and breaking means connectible through the circuit-closing key with the signal-operating circuit; a key locking and releasing device, and electrically-operated time-regulating means controlling the release of the key and itself controlled from the circuit making and breaking means.

10. In combination with a circuit-closing key adapted to control the circuit between a signal-producing device and a generator; a locking device; a spring operating to throw off the key and open the circuit when the key is released; clock-train-operated circuit making and breaking means in the circuit controlled by the key; electrically-operated releasing mechanism in circuit with the circuit making and breaking means and controlled through the operating mechanism thereof to release the key and open the circuit at a predetermined period of time in the operation.
11. In combination with an electrically-operated signal-producing device, a generator in open circuit therewith and a circuit-closing key, a spring adapted to throw off the key and open the circuit controlled thereby; a series of spaced contact-segments, and a traveling circuit-closer in the circuit between the generator and the signal-producing device and adapted to transmit measured electrical impulses over the line through the movements of the traveling circuit-closer, a locking device, and electrically-controlled time-operated releasing means adapted to throw off the locking device and open the circuit at a predetermined point in the movement of the traveling circuit-closer.
12. In combination with an electrically-operated signal-producing device, a series of stationary contact-segments in open circuit therewith through a generator; a traveling circuit-closer, time mechanism operating the traveling circuit-closer, and variable electrically-actuated means adapted to break the circuit at a predetermined point in the movement of the traveling circuit-closer; said means being controlled by the traveling circuit-closer.
13. In combination a circuit-controlling key including a plunger movable longitudinally and also rotatable, a circle of contacts severally and separately in circuit with a source or sources of electrical power, and a circuit-closing contact operative under the rotation of the plunger to set the circuit-closer on a selected one of the contacts.
14. The combination with a circuit-closing key, including a plunger having longitudinal movement and adapted also to rotate, of a circuit-selecting device operative under the rotation of the plunger and including a circle of contacts which are terminals of a plurality of separate circuits, a circuit-closing spring connected with the plunger to be operated by the rotation thereof, and an indicating device connected to the plunger.
15. A circuit-controlling key including a longitudinally-movable plunger, a locking device, a spring adapted to return the plunger to position after depression and release, a circuit making and breaking device including stationary contacts and a movable contact time mechanism adapted to actuate the movable contact, means connecting the time mechanism with the plunger to wind up the same from the movement of the plunger, and plunger-releasing means electrically operated and controlled from the movable contact of the circuit making and breaking device.
16. The combination of a series of spaced contact-segments in circuit with one side of a generator, a second series of contact-segments separately and severally in open circuit with the generator placed in alternate order with the first-named segments, a sound-producing device in circuit with the first-named series of segments, a circuit-breaking device separately in circuit with each of the contact-segments of the second series, and a mechanically-operated traveling circuit-closer connectible with the other side of the generator and means for closing the circuit between the generator and a selected one of the segments in the second series.
17. The combination with a series of contact-segments arranged in a circle at intervals apart around a common axis and interposed in the circuit between a sound-producing device and a source of electrical power, of a traveling time-operated circuit-closing device adapted by its movement to alternately open and close the circuit and operate the sound-producing device, and an electrically-operated circuit-breaking means including a second series of contact-segments alternating with those of the first-named series and separately connected in circuit with the circuit-breaking means and the source of electrical power, and means electrically controlled by the traveling circuit-closer to throw the current on any selected one of the contact-segments in the second series to the exclusion of the rest.
18. A circuit-controlling key adapted by a longitudinal movement to open and close the circuits controlled and by a rotary movement to reverse the connection between the circuits, including a plunger longitudinally movable and rotatable, and a contact-block on the plunger composed of insulated contact-pieces in separate pairs in one of which the contacts are divided axially of the plunger and are changed as to position by the rotation thereof, and the contacts in the other set are divided circumferentially and are not affected by such rotation.
19. A mechanically-operated circuit-closing device adapted to deliver plural signals to a line, a controlling-key provided with a selector, and means whereby the mechanism operating the circuit-closer is set in motion by a single movement of the key.
20. A time-regulated ringing-key for telephone-lines, including a traveling circuit-closer, mechanism operating the same, a controlling-key, and means whereby the operating mechanism is set in motion by a single movement of the key, and variable stop mechanism adapted to arrest the circuit-closer at a given point in its travel.
21. In a telephone-exchange, a mechanically-operated circuit-closing device adapted to de-

- liver plural signals to a line, time-regulating mechanism controlling the intervals between the signals, a controlling-key operating to throw the time-regulating mechanism into action, and a key-locking device operating to hold the key in an inoperative position and prevent a movement of the key to deliver a second signal during the operation of the circuit-closing device.
22. In a telephone-exchange, a mechanically operated circuit-closing device adapted to deliver plural signals to a line, time-regulating mechanism controlling the intervals between the bells or units of sound composing a plural signal, a controlling-key operating to throw the line-regulating mechanism into action, and a key-locking device controlled by the time-regulating mechanism, operating to hold the key in an inoperative position and prevent a movement of the key to deliver a second signal during the operation of the circuit-closing device.
23. In a signaling device, a plurality of signaling-circuits, a selector therefor, a cut-out, mechanism for locking the cut-out in an operative position and means for variably releasing the lock.
24. In a signaling device a plurality of signaling-circuits, a selector therefor, a cut-out, a circuit provided with mechanism for locking the cut-out in an operative position, and means for variably releasing the lock.
25. In a signaling device, a plurality of signaling-circuits, a selector and a circuit-closer therefor, a circuit provided with a cut-out and mechanism for locking the cut-out in an operative position, and means for variably releasing the lock.
26. In a signaling device, a plurality of signaling-circuits, a selector and a circuit-closer therefor, a circuit provided with a cut-out and with means for locking the cut-out in an operative position, said cut-out being common to the signaling-circuits and to the locking-circuit.
27. In a signaling device, a plurality of signaling-circuits, a circuit provided with locking mechanism, an operating-key provided with a selector, a cut-out, and means for engaging with the lock, and a circuit-closer for the signaling-circuits.
28. In a signaling device, a plurality of signaling-circuits, a circuit provided with locking mechanism, and an operating-key provided with a selector, a cut-out, and means for engaging with the lock, and a mechanically-driven circuit-closer for controlling the signaling-circuits, and the locking-circuit.
29. In a signaling device, a plurality of signaling-circuits, a circuit provided with locking mechanism, a longitudinally and rotatably movable key provided with an indicator, a selector, a cut-out and means for engaging with the lock, and a circuit-closer for controlling all of said circuits.
30. In a signaling device, a plurality of signaling-circuits, a circuit provided with locking mechanism, and with a plurality of contacts, a contact common to all the contacts of said circuits, a key provided with an indicator, a selector, a cut-out and means for engaging with the lock, and a circuit-closer for engaging with the contacts of all the circuits.
31. In a signaling device, a plurality of signaling-circuits, a circuit provided with locking mechanism and with a plurality of contacts, one of which is common to all the contacts of the signaling-circuits and the others are arranged to alternate therewith, a key provided with an indicator, a selector, a cut-out and means for engaging with the lock, and a circuit-closer for engaging with the contacts of all the circuits.
32. In a signaling device a plurality of signaling-circuits, provided with contacts arranged in a circle, a circuit provided with locking mechanism and with a plurality of circuits arranged concentrically relatively to the contacts of the signaling-circuits, one of said contacts being circular and the others alternating with the contacts of the signaling-circuits, a key provided with an indicator, a selector, a cut-out and means for engaging with the lock, and a traveling circuit-closer for engaging with said circularly-arranged contacts.
33. In a signaling device, a plurality of signaling-circuits arranged in two sets, a circuit provided with locking mechanism, a longitudinally movable and rotatable key provided with a cut-out, and means for engaging with said lock, said cut-out comprising two sets of electrically-connected contacts, separated from each other, the contacts of each set being insulated from each other, the insulation being arranged longitudinally of the key in one set and circumferentially in the other, and a circuit-closer for engaging with signaling-circuits.
34. In a signaling device, a plurality of circuits, a selector and a traveling circuit-closer therefor, an indicator, and means for simultaneously operating the selector and the indicator, said indicator being adapted to retain its position after being set until it is moved therefrom by the operation of said means in selecting another circuit.

In testimony that I claim the foregoing I have hereunto set my hand and seal.

FRANK W. ALSTON. [L. S.]

Witnesses:

JOHN RALPH WILSON,
EDWARD E. OSBORN.
